UNITED STATES PATENT OFFICE.

MICHAEL HAGARTY, OF WEST BAY CITY, MICHIGAN.

RAILWAY-TIE.

SPECIFICATION forming part of Letters Patent No. 395,134, dated December 25, 1888.

Application filed August 25, 1888. Serial No. 283,801. (No model.)

To all whom it may concern:

Be it known that I, MICHAEL HAGARTY, a citizen of the United States, residing at West Bay City, in the county of Bay and State of Michigan, have invented certain new and useful Improvements in Railway-Ties; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to improvements in metal ties for railroads, and pertains more especially to that class of metal ties which are formed of two longitudinal sections having laterally-extended flanges to receive and 20 support the rails, and provided with upwardly-projecting clutching devices for engaging with the rail-flanges to retain the rails thereon; and the invention consists in means for retaining the said tie-sections in a proper position 25 in relation to each other, and in the locking devices for retaining the clutching devices in engagement with the rail-flanges, and in the combination, arrangement, and construction of the several parts of the device, as I 30 hereinafter more fully describe, and especially point out in the claims.

The objects of my invention are to provide 35 a railroad-tie of metal, which is at the same time cheap and easily constructed and also durable and effective in its operation, and also to arrange a metal railroad-tie with suitable 40 devices for clamping the rail in position, and with locking devices whereby the said clamping devices are held in position for securing the rail to the tie; and a further and more 45 important object is to provide a railway-tie which is arranged to quickly clamp the rail in position or to release the same, as desired, and which will at all times retain the rails in proper position relative to each other, and 50 which may be easily ballasted and supported, whereby a great saving in labor of railway construction and repairs is obtained, and a more lasting, permanent, and substantial road is provided, which greatly reduces the liability of accident and the cost of operation.

My invention is illustrated in the accompanying drawings, in which—

Figure 1 represents a side view, in elevation, of my improved railway-tie, showing the rails clamped in position; and Fig. 2 is a plan view of the same. Fig. 3 represents the same with the parts in position before the rail is clamped, and Fig. 4 is a plan view of Fig. 3. Fig. 5 is an end view of Fig. 1. Fig. 6 is a section of Fig. 1 taken at *x x*. Fig. 7 is a section of Fig. 1 taken at *y y*. Fig. 8 is a view in perspective of the tie-section, or one-half of the improved tie, before the parts are joined together. Fig. 9 is a view in perspective of one end of the part shown in Fig. 8, with the rail-clamps in a modified form.

Similar letters designate the same parts throughout the several views.

Referring to Fig. 8, *a* represents a bar or 70 plate of iron rolled to the required thickness and with its upper edge turned outward, forming an upper flange, *b*, at right angles with the vertical body portion *c*, and, as shown in the illustration, the lower edge is also turned 75 outward in the same direction and formed into a lower flange, *d*, the plate or bar *a* being cut to the required length to form a railway-tie. In the central portion of the vertical body *c* is formed a longitudinal slot, *e*, and 80 the end portions of the body are also provided with the oblique slots *f* and *g*, which, for convenience, are shown as inclined in the same direction. Through the central portion 85 of the upper flange, *b*, is formed a transverse slot, *h*, and near the ends of the flange *d* is provided the raised clamping devices *i* and *j*, which may be formed, as shown in Fig. 8, by 90 partially cutting the portion from the plate and raising it upwardly to the required distance; or, as shown in Fig. 9, the clamping portion may be formed separately and rigidly attached to the plate by bolts or rivets *k*.

Referring now to the remaining illustrations shown in the drawings, the improved 95 railway-tie is formed by placing two of the before-described longitudinal tie-sections, *a* and *a'*, with the outer surfaces of their vertical body portions *c* and *c'* bearing against each other and with their flanges projecting 100 in opposite directions. This brings the central slots, *e* and *e'*, opposite or coincident with

each other, and through these slots is passed a bolt, *m*, which is provided with washer *n* and a nut, *l*, which is screwed to a position to hold the parts against each other, but still 5 allow a longitudinal movement thereof, if desired. This position of the sections *a* and *a'* also brings the clamping devices in a position that the clamps *i* and *j* of the section *a* will reach upon or engage with one side flange of 10 each rail, while the other clamping-pieces, *i'* and *j'*, of the section *a'* will reach upon and engage with the opposite side flanges of the rails. When the tie-sections are moved to a 15 position for securing the rails, as shown in Figs. 1 and 2, and in which position, also, the oblique end slots, *f* and *g*, in the section *a* cross the oblique slots *f'* and *g'* in the section *a'*, and which of course incline in the opposite direction and leave free openings at the cross- 20 ings of the slots through both portions *c* and *c'*, and through which, when the rails are clamped in position, are passed the bolts *o*, provided with suitable washers, *q*, and nuts *p*, which are screwed tightly down to retain 25 the plates rigidly in position for holding the rails in place.

In practice the improved ties are placed in position upon the road-bed and resting upon the lower flanges with the bolts *o* removed 30 and the sections *a* and *a'* moved to the position shown in Figs. 3 and 4. The rails are then laid in position between the clamping devices, a wrench, *s*, provided with downwardly-projecting lugs *r*, is placed with the 35 lugs *r* in engagement with the slots *h* and *h'*, which on operating the wrench in the required direction moves the tie-sections end- 40 wise in opposite directions and closes the clamping devices *i* and *j* and *i'* and *j'* upon the base-flanges of the rails. This position of the tie-sections then provides openings at the crossings of the oblique slots *f* and *f'* and *g* and *g'*, through which the bolts *o* are passed, and the nuts *p* then being tightly screwed in 45 place the parts are firmly locked and held in position, the oblique slots being so arranged that no matter what reasonable variation may exist in the rail-flanges they will cross each other and form a free opening for the bolts *o*, 50 which, when in position, firmly lock the tie-sections, as the oblique form of the slots prevents any longitudinal movement of the tie-sections so long as the bolts are in position, and the rails and clamping devices prevent 55 any vertical movement of the tie-sections.

The clamping devices *i* and *i'* and *j* and *j'* are shown as formed by cutting out and "striking up" a portion of the flanges *b* and *b'*; but the same may be formed of separate pieces 60 and attached securely to the surface of the flanges or tie-surface proper, as shown in Fig. 9, or in any other convenient manner.

It will be seen, of course, that by forming the tie-sections *a* and *a'* as set forth a great 65 advantage is gained in the manufacture and shipping of the parts, as only one set of

punches and dies is required to construct the sections, both being the same, and that no especial care and attention are needed to put the parts together to form the tie complete, 70 and the tie sections and bolts can be forwarded separately to their destination and put together as needed for use.

Another and great advantage is the ease with which a railway can be constructed with 75 the improved ties and the effective and permanent support afforded by the clamping devices and the tie-surface for the rails, all of the clamps closing firmly against the lateral edges of the rail-flanges, as well as over the 80 same, so that a more solid and uniform support for the rail is obtained, and the tie-sections being all of the same pattern, when the rails are secured to the ties they are at once brought to a uniform gage, from which there 85 is no liability or chance of departure.

The width of the lower flanges, *d* and *d'*, may be regulated to suit the circumstances in which they are placed and the material of the road-bed, and, as shown in Fig. 5, may be 90 made quite narrow to permit the ballast to be tamped beneath the upper flanges in order to level and support the rails, or may be formed wider, as shown in Fig. 7, so that they will operate to support the rails upon the 95 road-bed independently from the upper flanges. I do not wish it to be understood, however, that I confine my invention entirely to the precise form of clamping devices or to the form of locking device herein shown and 100 described, as either may be changed and still perform substantially the same operations; but

What I do claim, broadly, as my invention, and desire to secure by Letters Patent, is— 105

1. As a new article of manufacture, a railway-tie section consisting of a rolled-metal plate having the vertical body portion *c*, provided with the central longitudinal slot, *e*, and the oblique end slots, *f* and *g*, and having the 110 upper horizontal flange, *b*, provided with the cut-out and raised clamping devices *i* and *j* and the central transverse slot, *h*, and having the lower horizontal flange, *d*, substantially as and for the purpose set forth. 115

2. The combination, in a railway-tie, of the vertical longitudinal sections secured together side by side and capable of a longitudinal movement in relation to each other, and provided with laterally-projecting upper 120 flanges and locking devices, as the diagonal slots cut through the said vertical sections and crossing each other, and the bolts passed through the crossings of the said slots for retaining the said clamping devices in engagement with the rails, substantially as set forth. 125

3. The combination, in a railway-tie, of the tie-section *a*, having in its body portion the longitudinal slot *e* and the oblique slots *f* and *g*, and having the longitudinal flange *b*, provided on its upper surface with the rail-clamping devices *i* and *j*, with the tie-section 130

a' placed with its side against the side of the said section *a*, and having in its body portion a slot, *e'*, coincident with the said slot *e*, and the oblique slots *f'* and *g'*, crossing the slots 5 *f* and *g* and provided with a flange, *b'*, having the raised clamping devices *i'* and *j'*, and the bolt *m*, passed through the said slots *e* and *e'*, and the bolts *o*, passed through the said

oblique slots, substantially as and for the purpose set forth.

In testimony whereof I affix my signature in presence of two witnesses.

MICHAEL HAGARTY,

Witnesses:

JAS. E. THOMAS,

W. H. POWER.
